UNITED STATES PATENT OFFICE

167,938

TRAILER DOOR FASTENER

George M. Grindstad, Verona, Wis., assignor of one-half to Olin Bjornstad, Madison, Wis.

Application June 4, 1951, Serial No. 15,415

Term of patent 7 years

(Cl. D14—6)

To all whom it may concern:

Be it known that I, George M. Grindstad, a citizen of the United States, residing at Verona, county of Dane, State of Wisconsin, have invented a new, original, and ornamental Design for a Trailer Door Fastener, of which the following is a specification, reference being had to the accompanying drawing, forming a part hereof.

The dominant features of my design reside in those portions shown by means of full lines.

I claim:

The ornamental design for a trailer door fastener, as shown and described.

GEORGE M. GRINDSTAD.
